PACKAGE

Howard B. Tolley, Upper Montclair, N. J., assignor to National Biscuit Company, New York, N. Y., a corporation of New Jersey

Application October 29, 1938, Serial No. 237,646

5 Claims. (Cl. 99—171)

My invention relates to packages and particularly to a package in which two or more ingredients or articles are packaged and kept separate until such time as the purchaser may want to use them when the package may be manipulated to mix the two ingredients or articles, if mixing be desired, or it may be opened and the articles removed separately, if that be preferred.

10 I have illustrated my invention embodied in a package for doughnuts, wherein the doughnuts and sugar are packed in a single container on opposite sides of a flexible separator, which separator will bend when the package is inverted and shook so as to sift the sugar over the doughnuts and coat them uniformly.

Doughnuts, both sugared and plain, are distributed now to a very large extent in sealed packages containing either six or twelve, which 20 packages are put up at the bakery. Plain doughnuts in their packages reach the consumer in good condition, but with sugar coated ones, the sugar tends to coalesce and also absorbs grease which detracts from both the appearance and 25 saleability of the articles. My invention overcomes this difficulty by keeping the sugar and doughnuts separate until the consumer wants to eat them. Another disadvantage attendant upon sugaring the doughnuts before packaging is 30 that the coating of sugar must be made heavier or thicker than needed, because a considerable part of it will fall off due to handling and there must be enough left clinging to the doughnuts to thoroughly sugar them when they reach the 35 ultimate consumer. This excess sugar that ordinarily is wasted and adds to the expense of the doughnuts is saved by the present invention, because I place in the container only the amount of sugar necessary to properly coat the doughnuts. 40 My invention also has this advantage, that the consumer can control the amount of sugar on the doughnuts, that is, they can be sugared lightly or heavily, or they can be used plain by opening the package without inverting or shaking it. Still other advantages of my 45 invention are the low cost of the package, its ease of filling and sealing, and the fact that it is not necessary to break, tear or open any part of the package in order to dust the sugar over the doughnuts, or mix whatever ingredients may be contained in it. Other advantages and uses 50 of the invention will be apparent to those skilled in the packaging or bakery arts.

55 In the accompanying drawing, I have shown

an embodiment of my invention wherein Fig. 1 is a perspective view of a doughnut package; Fig. 2 is a cross sectional view thereof, taken as on the line 2—2; and Fig. 3 is a similar sectional view of the package inverted.

5 A cardboard carton which is shown as a shallow rectangular cardboard tray 5 of a length suitable to hold a number of doughnuts 6 stacked on edge, has its sides 7 cut away at 8 so as to display the contents effectively. When making up the 10 package, the tray 5 is first set up by turning up the sides 7 and interlocking the flaps 9, 10 at each end. A quantity of sugar 11, sufficient to sugar the number of doughnuts that the tray will hold, is then placed in the bottom and covered 15 with a sheet of flexible material 12 which preferably is a grease resistant material as wax paper, Cellophane and the like that will prevent grease from the doughnuts 6 penetrating to the sugar 11. This flexible sheet is approximately 20 the size of the tray or carton and fits fairly close to the side and end walls so as to cover the sugar, but is loose along at least one side, and preferably 25 along both sides. The stack of doughnuts 6 is next placed in the tray on the separator 12. The 30 entire package (when an open tray is used) is then enclosed in a wrapper 13 which may be cellophane that is folded over the ends as at 14 and sealed by heat or otherwise against the bottom of the tray.

35 After the packages have been sealed, they are packed for shipment and handling with the sugar side down and carefully kept that way until delivery to the store. When a purchaser wishes to sugar the doughnuts, he turns the sealed package upside down which causes the flexible separator 12 to bend down at the two sides, as shown in Fig. 3. This lets the sugar 11 trickle or sift 40 down over the doughnuts and by shaking the package slightly, the doughnuts become evenly coated. If only a light coating is desired, the amount of shaking will be less, and if plain doughnuts are wanted, the package will be opened without inverting or shaking it. It is thus seen 45 that my invention provides means whereby the consumer can have freshly sugared doughnuts at all times, or sugared to any desired degree. Also a minimum amount of sugar is required at a considerable saving to the baker. The package 50 as a whole presents an attractive appearance, effectually displays the contents, and avoids the unsightly, sticky appearance that usually accompanies bakery sugared doughnuts.

55 When a more durable package is required, the

tray 5 may be replaced by a cardboard carton that completely encloses the doughnuts, in which case the outer wrapper may be omitted.

I have shown doughnuts and sugar contained 5 in the package, but it is within the contemplation of my invention that it may be used with other articles and materials. For example, two or more ingredients of a chemical compound, mixture or medicine could be packaged in this manner, to be mixed just before using. Also cookies, 10 tarts, candies or other foods could be packed instead of doughnuts.

Having thus described one form of my invention, what I claim and desire to secure by Letters 15 Patent is:

1. A package of the class described comprising a carton having a bottom wall, a flexible separator of substantially the same dimensions as the bottom wall insertable in the carton after a layer 20 of finely divided material has been placed on the bottom, and means for closing the top of the carton after other material has been placed in the carton and on said flexible separator, said separator serving to keep said two materials 25 separate when said carton is in upright position but sufficiently flexible to bend when the carton is inverted and permit the material that was below it to sift past its flexed edges and contact the material that was above the separator.
- 30 2. A merchandise package of the class described comprising a carton having a flat bottom and an open top, a layer of finely divided material on said bottom, a flexible separator overlying said material and loose along at least one side, a number of articles of larger size resting 35 on said separator and filling said carton but leav-

ing at least one edge of said separator free, and a wrapper enclosing and sealing said carton and contents.

3. A package of the class described comprising an open top rectangular tray, a loose rectangular separator of approximately the same dimensions as the bottom of the tray insertable therein after a layer of finely divided material has been placed therein, and a transparent wrapper for enclosing and sealing said tray and contents, said wrapper 10 being folded and sealed against the ends and bottom of said tray.

4. A package of doughnuts comprising a rectangular cardboard tray, a layer of sugar on the bottom thereof, a rectangular sheet of flexible 15 material covering said layer of sugar, a stack of doughnuts resting on their edges on said rectangular sheet and leaving the edges thereof free, and a wrapper enclosing and sealing said tray 20 and contents.

5. A merchandise package comprising a container having a layer of powdered material on the bottom thereof, a loose partition wholly within the container and supported on the powdered material and normally separating the powdered 25 material from the upper part of the container, a number of articles in the container resting on the partition, means for closing the container above the articles, whereby the articles and powdered material normally occupy different compartments 30 in the container, the partition being constructed and arranged so that upon inversion or shaking of the package the powdered material will sift past the partition and over the articles in the other compartment.
